RESUSCITATING APPARATUS

Louis V. Snyder and Thomas Leggerie,
Mount Vernon, N. Y.

Application August 16, 1934, Serial No. 740,180

5 Claims. (Cl. 128—28)

Our present invention relates to resuscitating apparatus, and aims to devise devices of the general character indicated, which are simple in construction, which are easy and economical to operate and assemble, and which are admirably adapted to perform the intended functions as hereinafter more specifically set forth.

In the accompanying specification we shall describe, and in the annexed drawing show an illustrative embodiment of the resuscitating apparatus of the present invention. It is, however, to be clearly understood that we do not wish to be limited to the exact construction described and shown herein for purposes of illustration only.

15 Before describing our invention in detail, we deem it advisable, briefly, to refer to the prior art in the field to which the present invention relates, the disadvantages thereof, and the manner in which the present invention overcomes and eliminates such disadvantages.

20 It has, heretofore, been the practise in applying artificial respiration to a non-breathing patient requiring the same, to alternately apply and relieve pressure on the back immediately below the patient's lower ribs so as to bring about compression and expansion of the lungs, thus forcing air out of the patient's body and introducing air into the patient's body because of the vacuum created upon the release of the pressure.

25 The method generally used is known as the Schafer "prone-pressure method". In this method the desired pressure is obtained by the use of the hands alternately pressing and then letting go so as to permit a resumption of the 30 normal position of the particular organs of the body affected.

35 There are certain disadvantages inherent in the use of such a method of resuscitation which disadvantages the present invention successfully overcomes. In the first place by using the hands to exert the necessary pressure, we necessarily bring into the picture the human element. By that we mean that it is most difficult to apply the proper amount of pressure, the length of time 40 that the pressure should be maintained before releasing the same, and the timing or cadence of the alternate application and releasing of the pressure. Furthermore, inasmuch as the person applying the artificial respiration is using his 45 hands, the latter are not free to do anything else, and it is often necessary that the mere application of artificial respiration is not sufficient to revive the patient, and auxiliary means must be 50 resorted to. Obviously, such means cannot be

resorted to as the hands of the person applying the artificial respiration are not free.

The present invention overcomes and eliminates these disadvantages by providing a means for practising the so-called "prone-pressure method" mechanically, thus eliminating the human element, assuring the proper amount of pressure being applied, the proper length of time for the application of each stroke of pressure, and assuring the timing or cadence of the applications and eliminating the necessity of changing operators which change always acts to the detriment of the patient. It furthermore permits the operator the free use of his hands so that should any auxiliary treatment be necessary in conjunction with the artificial respiration, the operator is free to carry out such treatment. Other advantages of the present invention will become obvious to those skilled in the art to which the present invention relates as the detailed description thereof progresses.

In the accompanying drawing:—

Fig. 1 is a side elevational view of the aforesaid illustrative embodiment of the resuscitating apparatus of the present invention;

Fig. 2 is a transverse sectional view of the same, taken along line 2—2 of Fig. 1; and

Fig. 3 is a perspective view of the same, illustrating the manner in which the entire apparatus may be collapsed, and thereby made portable.

Referring now more in detail to the aforesaid illustrative embodiment of the present invention, and with particular reference to the drawing illustrating the same, reference character 1 generally designates a platform sufficient in length when opened to support the body of a person requiring artificial respiration, the platform consisting, preferably, of three (3) sections hinged as at 1a and supported upon a series of legs 1b. Mounted beneath the central section of the platform 1 is an electric motor 2, the drive shaft of which operates, through a reducing gear train 3 (not specifically shown), a worm wheel 4. The worm wheel 4 is fixed upon a shaft 5 which is journaled in brackets 6 fixed to the under-side of the central section of the platform 1, and mounted upon the shaft 5 is a pair of cams 7 maintained in contact with a cross-bar 8 by means of expansion springs 9 to which the cross-bar 8 is fixed. The springs are coiled about 45 reciprocal rods 10, and abut the under-side of the central section of the platform 1, and discs 11 fixed to the lower ends of the rods 10.

The rods 10 are maintained at an angle other than a right angle with respect to the platform 55

1, and are reciprocable in bushings 12 fixed in the central section of such platform. The upper ends of the rods 10 are provided with notches 13 with which there are engageable thumbscrews 14 carried in clamps 15, the arrangement being such that the height of the clamps 15 from the platform 1 may be varied, as will also be the apparatus supported by such clamps, and which will now be described. Carried by the clamps 15 is a cross-bar 16, this cross-bar being supported in such manner as to be permanently but rotatably fastened to one of the clamps so as to allow the same to be swung about to permit the patient to be placed in proper position and being supported by the remaining clamp by means of a catch 11. The cross-bar 16 is provided with a series of notches 18 with which there is engageable a pair of thumbscrews 19 carried in clamps 20 adapted to support pressure applying elements 21 which may be in the form of padded knobs. The arrangement of the elements 21 is such as to permit their adjustment depending upon the size of the patient to be treated.

When not in use, the foregoing apparatus can be made portable by merely folding down the outer sections of the platform 1 as shown in Fig. 3 of the drawing, and providing the exposed apparatus above the central section of such platform with a cover A having a handle B as indicated in dotted lines in the same figure of the drawing.

This completes the description of the aforesaid illustrative embodiment of the present invention and the operation thereof may be briefly summarized as follows:

A person requiring artificial respiration is placed upon the platform 1, the cross-bar 16 being swung out of the way to permit this and then the cross-bar 16 is swung back and is raised or lowered, and the clamps 20 are longitudinally adjusted until the pressure applied elements 21 are brought into proper position in relation to the patient's back and immediately beneath the lower ribs. Then, after fastening the various elements in place by means of the thumbscrews 14 and 19, the motor 2 is operated to bring about the rotation of the shaft 5. Through the cams 7 the cross-bar 8 is moved away from the shaft 5 until the cams reach the maximum radius of operation. At that time the cross-bar 8 is returned to its normal position by the action of the springs 9. Through the rods 10 and cross-bar 16, the same motion is imparted to the cross-bar 8, and thus pressure is alternately applied and released upon the patient so as to bring about artificial respiration. Such artificial respiration may be continued until the patient is revived. The movement of the elements 21 is downwardly and forwardly and upwardly and rearwardly.

This completes the description of the operation of the aforesaid illustrative embodiment of the present invention, and it will be seen therefrom that by means of the resuscitating apparatus of the present invention the human element referred to in the earlier parts of this specification has been removed, the proper amount of pressure, and the proper amount of time for the exertion of such pressure can be obtained, the timing or cadence of the alternate application and relief

of the pressure is perfect, and the hands of the operator are free to provide the patient with any auxiliary treatment that may be necessary. In addition to these advantages, it will be clear that the apparatus is simple in construction, easy, and economical to assemble and operate, and exceedingly efficient in performing the intended functions. Other superiorities and advantages of the resuscitating apparatus of the present invention will be obvious to those skilled in the art to which the present invention relates.

What we claim as our invention is:

1. Resuscitating apparatus comprising a collapsible and portable platform, receptive of a patient requiring resuscitation, and supporting pressure applying means, and means for alternately moving said pressure-applying means downwardly and forwardly, and upwardly and rearwardly.

2. Resuscitating apparatus comprising a collapsible and portable platform, receptive of a patient requiring resuscitation, and supporting pressure-applying means, means to adjust said pressure-applying means against the patient's back adjacent his lower ribs according to his size, and means for alternately moving said pressure-applying means downwardly and forwardly, and upwardly and rearwardly.

3. Resuscitating apparatus comprising a collapsible and portable platform, receptive of a patient requiring resuscitation, and supporting pressure-applying means, cam-actuated means for moving said pressure-applying means downwardly and forwardly, and resilient means for returning said pressure-applying means to normal position by moving the same upwardly and rearwardly.

4. Resuscitating apparatus comprising a collapsible and portable platform supporting pressure-applying means, means to adjust said pressure-applying means against the patient's back adjacent to his lower ribs according to his size, cam-actuated means for moving said pressure-applying means downwardly and forwardly, and resilient means for returning said pressure-applying means to normal position by moving the same upwardly and rearwardly.

5. Resuscitating apparatus comprising a collapsible and portable platform receptive of a patient requiring resuscitation, a pair of pressure-applying elements reciprocably supported on said platform and adjustable against the patient's back adjacent his lower ribs according to his size, a source of power, and means intermediate said pressure-applying elements and said source of power to alternately move said pressure-applying elements downwardly and forwardly, and upwardly and rearwardly, said means including a cross-bar connecting said pressure-applying elements, cam means driven by said source of power cooperable with said cross-bar to impart said downward and forward movement to said pressure-applying elements, and spring means to impart said upward and rearward movement to said pressure-applying elements after said cam means has reached its maximum radius of operation.
